The ornamental design for a robot, as shown and described.

DESCRIPTION

FIG. 1 is a perspective view of a robot showing our new design;

FIG. 2 is a first side view of the robot of FIG. 1;

FIG. 3 is a second side view of the robot of FIG. 1;

FIG. 4 is a front view of the robot of FIG. 1;

FIG. 5 is a rear view of the robot of FIG. 1;

FIG. 6 is a bottom view of the robot of FIG. 1; and,

FIG. 7 is a top view of the robot of FIG. 1.

The broken line showing of the robot is included for the purpose of illustrating portions of the robot and forms no part of the claimed design.
